HOUSING DECK FOR A VIBRATORY COMPACTOR

Helmut A. Mann, West Bend, Wis., assignor to
M-B-W, Inc., Slinger, Wis.

Filed Dec. 23, 1974, Ser. No. 538,319

Term of patent 14 years

Int. Cl. D15—04

U.S. CL. D15—33

Fig. 3

Fig. 2

FIG. 1 is a perspective view of the housing deck for a vibratory compactor embodying the invention.

FIG. 2 is a similar perspective view of a housing deck for a vibratory compactor, this view being taken from the other side of the compactor.

FIG. 3 is a top view of the housing deck for a vibratory compactor.

FIG. 4 is a side view of the housing deck for a vibratory compactor.

The broken line disclosure in FIGS. 1 and 2 is for illustrative purposes only and forms no part of the claimed design.

I claim:

The ornamental design for a housing deck for a vibratory compactor, as shown and described.
